UNITED STATES PATENT OFFICE.

THOMAS HARRIS MARTIN, OF COLUMBUS, OHIO.

SQUEEZER FOR COLLAPSIBLE TUBES.

1,389,452.

Specification of Letters Patent. Patented Aug. 30, 1921.

Application filed February 5, 1920. Serial No. 356,539.

To all whom it may concern:

Be it known that I, THOMAS H. MARTIN, a citizen of the United States, residing at Columbus, in the county of Franklin and State 5 of Ohio, have invented certain new and useful Improvements in Squeezers for Collapsible Tubes; and I do declare the following to be a full, clear, and exact description of the invention, such as will enable others skilled 10 in the art to which it appertains to make and use the same.

This invention relates to squeezers for collapsible tubes, and more specifically to an improved device for expressing the contents, 15 such as shaving cream, for instance, from a collapsible tube.

One object of this invention is to provide a device of this character which consists of exceedingly few and simple parts which are 20 secured together without the use of bolts, rivets, solder or any fastening means other than the inherent elements of the essential supporting and working parts of the device, thereby minimizing the cost of manufacture 25 and maintenance while providing a structure that is very easily and conveniently operated, and which presents an unusually pleasing appearance.

Another object is to provide a device of 30 this character in which a single pressure roller coacts with the shelf or table to squeeze the tube, thereby eliminating the usual second roller, at the same time providing an exceedingly effective support for holding the 35 mouth of the tube in an elevated position, the roller being spring-pressed toward the table to compensate for different thicknesses of each collapsible tube.

Other objects and advantages will be 40 pointed out or implied in the following details of description, in connection with the accompanying drawings in which:

Figure 1 is a front elevation of my improved device.

Fig. 2 is a sectional view along the line 2—2 of Fig. 1.

Fig. 3 is a sectional view along the line 3—3 of Fig. 2.

Fig. 4 is a sectional view along the line 50 4—4 of Fig. 1.

Referring to these drawings in detail, in which similar reference characters corre-

spond to similar parts throughout the several views, and in which a shaving brush 1 and a support 2 are illustrated in order to show 55 the complete device as manufactured and marketed, the invention consists in the details of construction which will now be specifically described as follows:—

The plate or table 3 is apertured at 4 to 60 receive the shanks 5 of a pair of journal bearings 6. A pressure roller 7 is journaled in these bearings and a hand-wheel 8 is secured to one end of the roller 7 and is manually operable for turning the roller. The 65 roller 7 is provided with a longitudinal or axially parallel groove 9 in which the flat end E of the collapsible T tube is insertable.

A pair of thumb screws 11 have threaded engagement with the interior of the hollow 70 shanks 5, and a pair of helical springs 12 surround the shanks 5 and have their upper ends seated in countersunk portions of the openings 4. Each of the thumb screws preferably comprises a knurled disk 13 and a 75 substantially flat finger piece 14, the former being convenient for affecting adjustments when the screws 11 work with relative ease, and also constituting spring seats against which the outer or lower ends of the springs 80 12 press for the purpose of yieldingly holding the roller 7 in such close proximity to the table 3 as to readily coact with the latter for squeezing and flattening the tubes. The table 3 is preferably formed with a concaved 85 and polished depression 15 which serves as a guide for the user in placing the tube between the table 3 and roller 7, also preventing the tube from winding helically on the roller 7 and coming into contact with the 90 journal bearing 6.

The table 3 is apertured and screw-threaded at 16, and the upper screw-threaded end of a standard 17 is fitted in this central aperture and coacts with a base or disk 18 95 for supporting the table 3 in spaced relation above a table or shelf on which the base 18 is intended to rest, and this base is provided with screw holes, one of which is illustrated at 19, so that the unitary device may be secured in any desired convenient position. It should be understood that the base 18 can be secured to a vertical surface if desired, so that the mouth of the paste tube is 100

elevated to a still greater extent than it is shown to be in Figs. 2 and 4, in which case, however, the brush support 2, being of wire, can be bent to extend at right angles to its 5 present position.

In operating the device, the slot or groove 9 is turned substantially at right angles to the position indicated in Fig. 4, the flat end portion 10 of the tube is inserted therein, 10 and the hand-wheel 8 is turned in the direction of the arrow in Fig. 4, thereby bending the flat end portion of the tube and pulling it through the space between the roller 7 and plate or table 3. The flat end 10 is substantially twice as thick, in practice, as the 15 adjacent flattened portion, and the springs 12 yield to permit this relatively thick portion to pass through said space. The cap of the tube is removed, of course, to permit 20 the shaving cream or other contents of the tube to be expressed through its mouth, and when a sufficient quantity has been obtained from the tube, its cap is replaced, and the pressure of the springs 12 maintains sufficient friction between the tube and the plate 25 3 to prevent accidental retrograde movement of the roller 7. After a considerable quantity of the material has been expressed from the tube, and the roller 7 has turned a complete revolution, the flattened portion of 30 the tube begins to wind upon itself, thereby thickening the material which must be passed through the space between the plate 3 and roller 7, and the springs 12 compensate for this additional thickness. In view 35 of the fact that some collapsible tubes are of thicker and stiffer material than others, and of the fact that some pasty or creamy contents of such tubes are thicker or more 40 nearly solid than others, it is necessary to regular the tension of the springs 12, and the thumb screws 11 serve to effect this function.

The screw-threaded engagement of the 45 standard 17 with the plate or table 3 enables the latter to be quickly and easily removed from the standard when desirable, and moreover in view of the fact that this single standard is connected to the plate 3 at a 50 point between the apertures 4, this provides unobstructed spaces into which the thumb screws 11 extend, so that there is no interference with the hand of the user in obtaining quick and easy access to the thumb 55 screws.

Although I have described this embodiment of my invention very specifically it is not intended to limit this invention to the exact details of construction and arrangement as described and illustrated, but changes may be made within the scope of the inventive ideas as implied and claimed.

What I claim as my invention is:

1. In a device for compressing and forc-

ing the entire contents from a collapsible 65 tube, a support including a horizontal plate provided with a substantially flat upper face and with oppositely disposed apertures, bearing blocks including hollow internally screw-threaded shanks extending through 70 said apertures, headed adjusting screws threaded in said shanks, coiled springs surrounding said screws and shanks between the plate and heads of the screws, permitting yielding of the bearing blocks, a combined pressure and feed roller carried by 75 said bearing blocks, means for connecting the tube to the roller, and means for imparting rotation to said roller.

2. In a device for expressing the contents 80 of a collapsible tube, a support including a table having a flat upper face with a transversely extending guide groove formed therein, said groove merging at its inner end into the flat face of the table and being 85 curved to conform to the tube which rests therein, and a yieldably mounted combined pressure and feed roller carried by the table.

3. In a device for compressing and forcing the entire contents from a collapsible 90 tube, a base, a standard rising therefrom, a horizontally disposed substantially rectangular plate secured to the upper end of said standard, said plate having a flat upper face and being provided with a centrally disposed 95 transversely extending guide groove which is of a greater depth at its outer end and merges at its inner end into the flat face of said plate, said groove being curved to conform to the shape of the tube which rests 100 therein, said plate being also provided adjacent its opposite ends and in its under faces with sockets and communicating openings which extend vertically therethrough, bearing blocks including hollow internally screw-threaded shanks, the latter extending through said openings and sockets, headed 105 adjusting screws co-operative with the screw-threads of said shanks, coiled springs surrounding said screws and shanks, bearing 110 at one end against the heads on said screws and being disposed at the opposite ends in said sockets and resting against the inner ends of the latter, permitting yielding of the bearing blocks, a combined pressure and feed roller including reduced ends constituting studs, the latter being journaled in 115 said bearings, said roller being provided in one side with a longitudinal groove for reception of the usual reinforced end of the 120 tube to be compressed, and a hand-wheel for imparting rotation to said roller.

4. In a device for compressing and forcing the contents from a collapsible tube, a support including a table provided at spaced 125 points with vertical openings extending therethrough, bearing blocks including shanks extending through said openings,

spring means under said table and acting on said shanks for moving said bearing blocks downwardly, a combined pressure and feeding roller including reduced ends journaled in said bearing blocks, said roller being equipped with means to permit connection of the closed end of a collapsible tube there-

to, and means connected with one of the reduced ends of the roller for imparting rotation to the latter.

In testimony whereof I have hereunto set my hand.

THOMAS HARRIS MARTIN.
